US0D1019253S

(12) **United States Design Patent** (10) **Patent No.:** **US D1,019,253 S**
(45) **Date of Patent:** **** Mar. 26, 2024**

(54) **FOOD PROCESSOR**

(71) Applicant: **WANTBO.CO., LTD**, Taoyuan (TW)

(72) Inventor: **Chih-Te Lin**, Taoyuan (TW)

(73) Assignee: **WANTBO.CO., LTD**, Taoyuan (TW)

(**) Term: **15 Years**

(21) Appl. No.: **29/817,126**

(22) Filed: **Nov. 29, 2021**

(30) **Foreign Application Priority Data**

Jun. 17, 2021 (TW) 110303158

(51) **LOC (14) Cl.** **31-00**

(52) **U.S. Cl.**

USPC **D7/376; D7/384**

(58) **Field of Classification Search**

USPC D7/302, 303, 309, 312, 316, 317, 318, D7/319, 321, 322, 323, 326, 350.1, 350.3, D7/354, 357, 358, 368, 376, 372, 377, D7/378, 379, 380, 381, 382, 383, 384, D7/385, 386, 387, 399, 402, 412, 413, D7/414, 415, 543, 544, 560, 562, 565, D7/586, 587, 588, 668, 673, 674, 675, D7/677, 678, 693, 694, 672, 311

(57) **CLAIM**

The ornamental design for a food processor, as shown and described.

DESCRIPTION

FIG. 1 is a perspective view of a food processor showing my new design;

FIG. 2 is a front view thereof;

FIG. 3 is a rear view thereof;

FIG. 4 is a left side view thereof;

(Continued)

FIG. 5 is a right side view thereof;
FIG. 6 is a top view thereof; and,
FIG. 7 is a bottom view thereof.
